UNITED STATES PATENT OFFICE.

EUGENE G. CRUMP, OF AKRON, OHIO, ASSIGNOR TO PERFECTION RUBBER-METAL HORSESHOE CO., OF AKRON, OHIO, A CORPORATION OF DELAWARE.

HORSESHOE.

1,334,438.

Specification of Letters Patent. Patented Mar. 23, 1920.

Application filed October 6, 1919. Serial No. 328,777.

To all whom it may concern:

Be it known that I, EUGENE G. CRUMP, a citizen of the United States, residing at Akron, in the county of Summit and State 5 of Ohio, have invented certain new and useful Improvements in Horseshoes, of which the following is a specification.

This invention relates to horseshoes of that class in which a shoe of rubber or other 10 elastic or equivalent material is stiffened and strengthened by embedding in it a shoe-shaped plate of steel or the like, and the object of the invention is to produce a shoe which is of feasible and practicable construction.

A further object is to produce a reinforced cushion shoe in which the reinforcement is in the form of a thin flat metal plate having a depending toe flange and a pair of 20 depending heel flanges for the purpose of not only increasing the wearing qualities, but also to coöperatively afford means for binding the cushioning part of the shoe irrevocably to the plate.

The advantage of a strong, durable, and 25 efficient shoe of light weight has long been recognized, as such a shoe would minimize the injurious results attendant on travel on paved streets or on long or fast travel over 30 rocky and uneven roads, and furthermore that such a shoe would conduce to the comfort of an animal when stabled as well as in travel and in a large measure prevent shoulder, knee, and hoof troubles, and also minimize danger of injury through kicking, 35 where a number of animals are confined, particularly in a car.

With the object of producing a shoe possessing the advantageous features above set 40 forth as objectives and incidentally a shoe of light weight, the invention consists in certain novel and useful features of construction and combinations of parts as hereinafter described and claimed; and in order 45 that it may be fully understood, reference is to be had to the accompanying drawing, in which:

Figure 1 is a view showing the shoe in inverted plan with the half of the cushioning body cut away in the plane of the upper 50 side of the reinforcing plate;

Fig. 2 is a section on the line II—II of Fig. 1, with the shoe in upright position;

Fig. 3 is a fragmentary section on the 55 line III—III of Fig. 1; and

Fig. 4 is a fragmental perspective view of the reinforcing plate.

Referring to the drawing in detail, 1 indicates a thin flat plate of sheet steel or the like of horseshoe form and provided at opposite sides with nail holes 2, and at its toe portion with an angular extension 3, part of the extension lying in the plane of the plate and being provided with substantially key-shaped holes 4, and the other part constituting 60 a depending arcuate flange 5. At the rear or heel ends of the shoe, the same is provided with depending flanges 6 of rearwardly bowed form, the front or inner sides of the flanges sloping downwardly or forwardly so as to constitute in effect undercuts or chambers 7. The rear ends of the shoe are also provided adjacent said flanges, which are preferably wider than the adjacent portions of the plate, with substantially 70 keyhole-shaped openings 8.

The plate described is completely embedded in a rubber or rubber composition or other elastic member 9 of horseshoe form, the front or convex face of the arcuate 80 flange 5 lying flush with the corresponding edge of the elastic body, and the convex sides of the heel flanges likewise standing flush with the rear or heel ends of said body, the rear or heel ends thereof being curved 85 to correspond with the curvature of said heel flanges.

The cushioning body thus completely overlies the plate, and it also underlies the same to the plane of the lower edges of the 90 said flanges, and fits in the undercuts or chambers 7 of the heel flanges. The elastic body is molded in place with nail holes 10 registering with the nail holes 2 of the plate, the nail holes in the body being in that portion thereof that underlies the plate. The body is molded and is of substantially greater width than the plate and hence encases the latter completely as explained, except the flanges thereof, the portions of 100 the body above and below the plate and in the plane of the margins thereof being united by portions which extend through the said elongated or keyhole-shaped openings in the plate.

A shoe made as described possesses the various features of advantage set forth as desirable and has proved in actual use exceedingly efficient and durable.

The toe and heel flanges can only coöp-

erate together in fastening the body integrally in place but do not detract from the cushioning properties of the body, because the latter completely overlies the plate, and 5 furthermore because the body below the plate and between said flanges lies flush with the latter and receives the greater portion of the impact of the foot upon the ground. The under surface of the body is 10 roughened on its toe and heel surfaces by molded ribs at 11 and 12 which serve to give a better grip on the road and coöperate with the metal flanges in guarding against slippage.

15 From the above description it will be apparent that I have produced a horseshoe which is light in weight, durable, and which affords protection to the animal wearing the same.

20 I claim:

1. A horseshoe comprising a body of elastic material, a metal plate of horseshoe form embedded in said body, said plate having a depending flange at its front edge flush with the corresponding edge of the said body, and depending flanges at its rear ends flush with the corresponding edges of the body and forming undercut chambers engaging the rear ends of the body to retain the engaged portions against the underside of the plate.
2. A horseshoe comprising a body of

elastic material, a metal plate of horseshoe form embedded in said body and provided with openings through which the portions of the body above and below the plate are integrally united, said plate having a depending flange at its front edge flush with the corresponding edge of the said body, and depending flanges at its rear ends flush with the corresponding edges of the body and forming undercut chambers engaging the rear ends of the body to retain the engaged portions against the underside of the plate.

3. In a horseshoe, a resilient body, a horseshoe-shaped plate embedded completely in said body, and provided at its front end with an angular extension comprising a portion in the plane of the plate and embedded therein and a depending arcuate flange also embedded in said body and flush at its front or convex side with the corresponding edge of the body; said plate also having depending heel flanges of greater width than the plate and embedded in said body with their rear sides flush with the rear edge of the body, the said heel flanges sloping downwardly and forwardly and forming undercut chambers receiving the rear ends of that portion of the body underlying the said plate.

In testimony whereof I affix my signature.
EUGENE G. CRUMP.
